UNITED STATES PATENT OFFICE.

HEINRICH RÜTT, OF RHEYDT, GERMANY.

CAN-OPENER.

No. 854,434.

Specification of Letters Patent.

Patented May 21, 1907.

Application filed July 13, 1906. Serial No. 326,014.

To all whom it may concern:

Be it known that I, HEINRICH RÜTT, a subject of the German Empire, residing at Rheydt, in the Kingdom of Prussia, Germany, have invented a new and useful Can-Opener, of which the following is a full and complete specification.

The object of the present invention is a contrivance for opening, preserved meat boxes, or other cans by means of a curved knife. The latter is carried by a hand lever which is pivoted to a stand in such a manner, that cans of different height and size may be readily opened.

15 In the accompanying drawing: Figure 1 is a side elevation of my improved can opener; Fig. 2 a detail of the knife with the supporting lever partly broken away, and Fig. 3 a section on the dotted line indicated in Fig. 2.

20 In the device shown the can opener is provided with a standard or upright *a*, perforated at suitable distances and held in position by a vise *b*. This vise is composed of upper and lower parallel arms integral with upright *a*, the lower arm being tapped for engagement with a clamp screw. The upright *a*, is embraced by a tubular slide *e*, which is perforated for the admission of a pin *f*, adapted to engage either of perforations of upright

25 *a*, so that in this way the elevation of the slide may be made to correspond to the height of the can to be opened. From slide *e*, projects an arm *e'*, to which is hinged at *e''*,

a vertically oscillating hand lever *c*, which carries the knife *d*. The placing of the tin 35 under the apparatus can, of course, be effected in any other manner, and, if desired, the lever *c* could be pivoted direct on the stand or upright. The stand is fixed to the top of the table or counter *h* by means of the vise *b*; 40 the tin to be opened is placed on the latter or on the table in such a manner that it is operated on by the knife depressed by the lever *c*, at the required spot. It is then turned around and, as the knife is curved, a 45 circular section will be cut from the tin. The opening of a tin is performed very easily by the new opener, and persons not possessed of much strength can operate it.

Having now fully described my invention, 50 what I claim as new and desire to secure by Letters Patent is:

A can opener provided with a perforated upright having a pair of integral parallel arms, a clamp screw engaging the lower arm, 55 a perforated tubular slide having a laterally projecting arm, a pin for locking the slide to the upright, a vertically oscillating lever pivoted to the arm, and a cutter secured to the lever, substantially as specified.

Signed by me at Düsseldorf, Germany, 60 this thirty-first day of May 1906.

HEINRICH RÜTT.
